Fig. 3

To all whom it may concern:

Be it known that I, Anne Ohman Williamson, a citizen of the United States of America, residing at Chicago, in the county of Cook and State of Illinois, have invented a new, original, and ornamental Design for a Brassière, of which the following is a specification, reference being had to the accompanying drawing forming a part thereof.

In the drawings:

Figure 1 is a front perspective view of a brassière showing my new design, the shoulder straps being broken away for convenience of illustration;

Figure 2 is a front view of the brassière of Figure 1, the body encircling portion of the brassière being shown extended; and

Figure 3 is a view similar to Figure 2, but of the rear of the brassière.

I claim:

The ornamental design for a brassière, as shown.
